[54] **INTERLAYER ENHANCEMENT OF
INTERIMAGE EFFECTS**

[76] Inventor: **James L. Graham, 44 Briar Hill,
Rochester, N.Y. 14626**

[21] Appl. No.: **879,574**

[22] Filed: **Feb. 21, 1978**

element comprised of a support and, as coatings on the support, a layer comprised of a silver haloiodide emulsion sensitized to green light and a layer comprised of a silver haloiodide emulsion sensitized to red light. Interposed between these layers is a colloidal silver layer. The presence of the colloidal silver produces a favorable interimage effect, as compared to that achieved in its absence.
